UNITED STATES PATENT OFFICE.

FRANK RHIND, OF BRIDGEPORT, CONNECTICUT, ASSIGNOR OF ONE-HALF
TO THE BRIDGEPORT BRASS COMPANY, OF SAME PLACE.

ACETYLENE-GAS GENERATOR.

SPECIFICATION forming part of Letters Patent No. 623,829, dated April 25, 1899.

Application filed August 5, 1898. Serial No. 687,767. (No model.)

To all whom it may concern:

Be it known that I, FRANK RHIND, a citizen of the United States, residing at Bridgeport, Fairfield county, Connecticut, have invented a new and useful Improvement in Acetylene-Gas Generators, of which the following is a specification.

My invention relates to means for decreasing the possibility of accident in the use of acetylene-generators, especially those of small size, as of portable lamps. It provides a relief-valve simple in character and protected from injury.

The accompanying drawing shows in elevation, partly broken away, a lamp embodying my invention.

1 designates a gas-generator formed with top 12 and outlet 13; 2, a valve-chamber provided with outlet 21; 3, a valve-seat; 4, a washer; 5, a valve, and 6 a spring.

In the example of my invention illustrated in the drawing the gas-generator 1 may also serve as a carbid-chamber or it may contain a separate receptacle, as a bag or box, (not shown,) for the carbid. From the top 12 of the generator 1 passes a gas-outlet 13, shown as a burner within a suitable combustion-chamber. Secured within the suitably-recessed top 12 is a valve-chamber 2, having an outlet 21, shown as a small tube leading to the tip of the burner 13. Adjustably secured, as by a screw-thread, in the lower end of the chamber 2 is a removable annular valve-seat 3, carrying a washer 4 of rubber or other packing material. A valve 5, which is preferably a disk of glass or other non-corrosive material, rests on the washer 4. A spring 6 bears against the disk 5 to hold it in place.

40 The operation of my device will be clearly understood from an inspection of the drawing.

Gas formed in the generator 1 escapes by the outlet 13 and may be lighted at once. If 45 for any reason an excess of gas is produced, it will lift the valve-disk 5 and permit the gas to flow through the relatively free outlet 21.

This, as shown, is contracted at its upper end to form a small orifice near the burner-tip, so that the gas is consumed at the flame. The 50 gas thus issuing from a small emission-orifice and under pressure burns with a clear flame and does not tend to smoke the reflecting-surfaces of the combustion-chamber. The strength of the spring 6 and the manual adjustment of the seat 3 predetermine the point at which the relief-valve acts.

It will be understood that my invention is not limited to the form, proportions, particular combination, or uses shown. In fact, many 60 mechanical alterations are possible without departing from its essentialities.

What I claim is—

1. In combination a gas-generator, a gas-burner connected with said generator, a relief-valve directly exposed to the gas-pressure in said generator and an outlet connected with said valve and adapted to convey gas passing said valve to a point adjacent to said burner, substantially as described. 70

2. In combination a gas-generator, a gas-outlet from said generator and provided with a burner-tip, a valve-chamber opening into said generator independently of said outlet, a valve-seat, a valve normally resting on said seat and adapted to be raised therefrom by gas-pressure in said generator and a gas-outlet from said chamber and adapted to convey gas passing said valve to a point adjacent to said burner, substantially as described. 75

3. In combination a gas-generator, a valve-chamber opening into said generator, a valve-seat, a disk of glass or other non-corrosive material normally resting on said seat and adapted to be raised therefrom by gas-pressure in said generator and an outlet from said chamber exterior to said generator, substantially as described. 85

4. In combination a gas-generator, a gas-burner connected with said generator, a valve-chamber opening into said generator, a removable valve-seat, a disk normally resting on said seat and adapted to be raised therefrom by gas-pressure in said generator and an 90

outlet-tube leading from said valve-chamber to a point adjacent to said burner, substantially as described.

5. In combination a gas-generator, a valve-chamber opening into said generator, a valve-seat, a spring-actuated disk normally resting on said seat and adapted to be raised therefrom by gas-pressure in said generator, means

substantially as described for manually varying the pressure of said disk on said seat to and an outlet from said chamber exterior to said generator.

FRANK RHIND.
